UNITED STATES PATENT OFFICE.

OLIVER M. EDWARDS, OF SYRACUSE, NEW YORK, ASSIGNOR TO THE O. M. EDWARDS COMPANY INC., OF SYRACUSE, NEW YORK, A CORPORATION OF NEW YORK.

WINDOW-LOCK CONSTRUCTION.

Application filed September 11, 1924. Serial No. 737,203.

This invention relates to windows as windows used in railway cars and vehicles, and more particularly to windows in which no sash counterbalancing means are used, or 5 windows which when not held in elevated position tend to close by gravity, and has for its object a particularly simple and efficient means by which the sash lock coacts with the rack to effect a sliding frictional resistance 10 to retard the dropping of the sash and prevent it from coming violently to a stop, and thereby prevent injury to the sash, the sash lock and the rack with which the sash lock coacts.

15 The invention consists in the novel features and in the combinations and constructions hereinafter set forth and claimed and described.

20 In describing this invention, reference is had to the accompanying drawings in which like characters designate corresponding parts in all the views.

25 Figure 1 is an elevation, partly broken away, of a window sash embodying my invention, the contiguous portion of the rack associated with the window frame being also shown.

Figure 2 is an enlarged fragmentary detail view of a preferred form of rack.

30 Figure 3 is a sectional view through the rack shown in Figure 2, the position of the bolt of the sash lock being shown in dotted lines.

35 Figure 4 is similar to Figure 2 of another form of my invention in which the teeth of the rack are straight.

Figure 5 is similar to Figure 2 in another form in which the teeth of the bolt are bevelled.

40 Figure 6 is a view similar to Figure 2 of another form of rack, in which both the teeth of the rack and the teeth of the bolt members are bevelled.

Figure 7 is a fragmentary elevation of a 45 corner of the sash provided with a different form of lock from that seen in Figure 1; and Figure 8 is a sectional view looking to the right in Figure 7 showing the rack and the bolt coacting therewith.

50 In window sashes, such as are used in railway cars and in which no counterbalancing means is used, oftentimes in lowering the window, the bolt comes violently in contact with the abrupt shoulders of the rack, and

suddenly stops the descent of the sash causing injury to the bolt member and also injury and tearing out the teeth of the rack. This is true particularly when the trainmen at the end of the line are in a hurry, to close all windows that are left open by the passengers and slam the windows closed.

This invention comprises the combination of a window sash having a sash lock provided with a movable bolt member, a window frame including a rack member coacting 65 with the bolt member, the teeth of said members being arranged to coact with sliding frictional resistance to retard the closing movement of the sash before the sash comes to a complete stop, so that the sash is prevented from coming suddenly to a complete stop.

In the illustrated embodiment of my invention, either the rack, or the bolt member or both of them may be provided with teeth 75 having inclined faces which act as a brake while the window is falling under its own weight or force tending to close it, the bevel being downwardly and outwardly. This bevel may be a straight bevel or a rounding 80 bevel.

1 designates the sash, which may be of any suitable form, size and construction, and 2 the rack which is fixed to the window frame. As will be understood by those skilled in the 85 art, the rack is usually arranged to have teeth 3 arranged obliquely relatively to the plane of the sash and the bolt 4 moves parallel to the plane of the sash and has an oblique face 5 arranged to press against the 90 rack. The sash lock may be of any suitable form, size and construction and is here shown as a spring pressed bolt 4 having spaced apart teeth 6, the bolt being operable by a pinch lever 7 arranged in juxtaposition 95 to a stationary handle 8 on the casing 9 of the sash lock.

As shown in Figures 2 and 3, the rack 2 is formed with rounding teeth 3, the upper half of these teeth constituting a rounding bevel 100 inclined downwardly and outwardly and the lower half constituting a bevel inclining downwardly and inwardly, that is, the apex of the curve is midway between the base of the tooth. During closing of the window, 105 the operator withdraws the bolt 4 by moving the pinch lever 7 downwardly and if the operator holds this pinch lever 7 in its opera-

tive position, he must necessarily let the sash down comparatively easily, but if he lets go of the handle 7 or gives the sash a downward push, the sash instead of being stopped suddenly by the bolt coming in contact with an abrupt shoulder as in the racks heretofore used, the bolt will ratchet over several of the teeth of the rack against the action of the spring of the bolt and hence apply a sliding frictional braking action to the sash, which brings it to an easy stop.

In Figure 2, the teeth 6 are spaced apart far enough to receive a tooth between them and the friction effect not only takes place while the teeth are riding over the upper half of the tooth of the rack, but also while the teeth of the bolt are riding over the lower half of the tooth 3.

In Figure 4, the rack 11 is shown as formed with teeth 12 having downwardly and outwardly inclined bevelled faces 13 and with a small abrupt shoulder 15 at the top of each tooth with which shoulder, the bolt 16 finally comes in contact when the sash is slowed down by the braking and ratcheting action of the bolt and rack.

In Figure 5, the rack 17 is shown with abrupt teeth 18 while the teeth 19 of the bolt 20 are shown as formed with bevelled faces 21 for coacting with the teeth of the rack to effect the braking action.

In Figure 6, both the teeth 22 of the rack 23 and the teeth 24 of the bolt 25 are shown as formed with coacting bevelled faces 26 and 27 which coact inclined plane fashion to effect the braking action.

In Figures 7 and 8, the rack is shown as coacting with a pivoted bolt 28 coacting with a rack 29 formed by corrugating a strip of metal, the rack having rounding corrugations or steps 30. The pivoted bolt 28 is formed with a rounding end 31 coacting with rounding teeth 30 of the rack 29 and is also formed with a tooth or shoulder 32 for hooking under a shoulder 33 usually at the lower end of the rack for the purpose of locking the window sash closed. The bolt 28 is mounted upon a rock shaft 34 journalled in the housing or casing 35 and having a handle 36 on the front side of the housing arranged in juxtaposition to a fixed handle 37. The housing 35 is mounted on the window sash as seen in Figure 1.

What I claim is:

1. The combination of a window sash having a sash lock provided with a movable bolt member, a window frame having a rack for coacting with the bolt member to hold the sash at different elevations, said rack having rounding bevel teeth, and the

bolt having a ratcheting movement and a tooth coacting with the teeth of the rack.

2. The combination of a window sash having a sash lock provided with a movable bolt member, and a window frame having a rack for coacting with the bolt member to hold the sash at different elevations, said rack having rounding bevel teeth, and the bolt having a ratcheting movement and spaced apart teeth for coacting with the rack, the teeth of the bolt being spaced apart a sufficient distance to receive a tooth of the rack between them.

3. The combination of a window sash having a sash lock provided with a movable bolt member, a window frame having a rack for coacting with the bolt member to hold the sash at different elevations, said rack having a ratcheting movement and rounding teeth with the apex of each tooth midway between the base of the tooth, and the bolt having a tooth coacting with the teeth of the rack.

4. The combination of a window sash having a sash lock provided with a rocking bolt member and a window frame having a rack for coacting with the bolt member to hold the sash at different elevations, the rack having a ratcheting movement and rounding teeth and the bolt member being shaped to enter between the rounding teeth and frictionally coact therewith to frictionally retard movement of the sash before the sash comes to a complete stop.

5. The combination of a window sash having a sash lock provided with a bolt member mounted to have a ratcheting movement, a window frame having a rack for coacting with the bolt member to hold the sash at different elevations, said rack having beveled teeth and the bolt having spaced apart teeth coacting with the teeth of the rack.

6. The combination of a window sash provided with a movable bolt member, a window frame having a rack for coacting with the bolt member to hold the sash at different elevations, said member having coacting teeth, the teeth of said member being shaped to act inclined plane fashion on each other to retard the movement of the sash before the sash comes to a complete stop and the bolt member having a ratcheting action in the same direction as its operating action and manual means for operating the bolt.

In testimony whereof, I have hereunto signed my name, at Syracuse, in the county of Onondaga, and in the State of New York, this 22nd day of August, 1924.

OLIVER M. EDWARDS.
